MANHOLE STEP

Herbert N. Morris, Sandusky, Ohio

Application November 18, 1939, Serial No. 305,084

6 Claims. (Cl. 228—46)

This invention relates to an improvement in members adapted to be set in cast concrete structures, and, more particularly, to cast iron steps for cast concrete manholes or similar structures 5 of cast concrete.

As is well-known, it is necessary to provide manholes or similar structures with steps set in the structure. Such steps are usually U-shaped members comprising a tread portion supported 10 by arms which are set in the structure. Such steps may be steel, but are preferably cast iron, due to the tendency of steel to corrode. Heretofore, the cross-sections of the step arms have been either rectangular or circular. The rectangular cross-sections were preferable to the circular cross-sections since they were stronger and could be secured more firmly in the concrete or mortar. Round cross-sections present a minimum surface to the mortar or concrete in which 15 they are secured and are prevented from loosening only by the adhesion of the mortar or concrete to the surface of the arm.

No particular problem of installation arises when steps having arms rectangular in cross-section are supported in brickwork, since the steps may be placed in position as the bricks are laid. When the steps having arms rectangular in cross-section are supported in cast concrete structures, however, installation problems arise. 20 The concrete must be cast around the arms of the steps which are inserted through the wooden or metal forms into which the concrete is poured. To insert the rectangular cross-sectioned step arms through the wooden form, a carpenter must 25 cut a rectangular opening in the form for each step arm with a keyhole saw or broach the hole with a chisel. This operation is time-consuming and expensive.

It is an object of this invention to provide a 30 step for concrete structures with arms having cross-sections which will permit the step to be set quickly and inexpensively into a wooden or metal concrete form and which will eliminate the necessity of keyholing or broaching step openings 35 through the form. It is another object of this invention to provide a cast iron manhole step arm which will have a cross-section of substantially maximum strength.

It is a still further object of this invention to 40 provide a manhole step which may be securely held in cast concrete by both adhesion and mechanical engagement between the step arm and the concrete which is cast about it. Other and further objects and advantages will be apparent

from the following specification, claims, and drawing in which:

Fig. 1 is a perspective view illustrating a manhole step made according to this invention;

Fig. 2 is a cross-section taken along the line 5 2—2 of Fig. 1;

Fig. 3 is a cross-section taken along the line 10 3—3 of Fig. 1;

Fig. 4 is a view similar to Fig. 2 but illustrating a modification of this invention; and

Fig. 5 is an elevation of a portion of a form drilled to receive a manhole step as illustrated in Fig. 1.

In the drawing, in which like reference characters refer to like parts, 10 is a manhole step 15 made according to this invention. Preferably the manhole step is of cast iron, though any other suitable material may be used, and is comprised of a tread 11 supported by a pair of parallel arms 12 and 13 disposed at right angles to the tread 20 11. As shown in Figs. 1 and 3, the tread 11 may be rectangular in cross-section and is preferably provided with a flat upper surface suitably knurled to prevent slipping and to afford an adequate foothold.

The arms 12 and 13 are of a suitable length to allow the step to be anchored in the cast concrete and to support the tread 11 away from the wall of the manhole or similar structure, so that the step affords an adequate depth of tread. As 30 shown in Figs. 1, 2, and 4, the cross-section of the arms 12 and 13 is comprised of a plurality of substantially tangent circular areas. The circular areas making up the cross-section of the arms may be of equal size, but are preferably of 35 different size, the larger circular area or areas being located in the upper portion of the cross-section in order to obtain the maximum strength for the amount of cast iron in the arm. In the preferred form of the invention, as shown in Figs. 1 and 2, the cross-section of the arm is substantially in the form of an inverted figure 8, being comprised of a larger upper circular area 15 and a smaller tangent lower circular area 16, the circular portions being joined by the fillets 17 and 18. In the preferred cross-section, the tension 45 load on the arms is carried by the larger circular portion 15 and the compression load is carried by the lower circular portion 16.

It is obvious that the circular areas making 50 up the cross-section of the arm need not be precisely tangent, but may be spaced apart or may intersect. Furthermore, the circular areas may be of any convenient number and may be arranged in any suitable manner. For 55

example, in the modified cross-section shown in Fig. 4, the cross-section is made up of three circular areas in a substantially clover leaf arrangement in which the larger upper circular portions 19 and 20 carry the tension load and the smaller lower circular portion 21 carries the compression load. Also, in order to provide mechanical engagement by the arms of the step against longitudinal movement in the concrete in which the arms are anchored, the ends of the arms may be curved in substantially parallel planes, as at 22 and 23 of the arms 12 and 13, respectively.

To insert the step 10 into a form prior to pouring the concrete of the structure, a suitable opening 24, as shown in Fig. 5, is provided in the form for each arm of the step by locating centers 25 and 26 spaced a vertical distance from each other equal to the vertical distance 20 *a* between the centers of the circular areas 15 and 16 of arms 12 and 13. Holes 35 and 36 which are equal in diameter to the circles 15 and 16, respectively, are then bored with ordinary augers. The nibs 27 and 28 protruding 25 between the tangent holes 35 and 36 may be removed with a chisel, or, because the nibs extend across the grain, by simply driving the end of an arm of the step through the holes 35 and 36.

30 After the steps are inserted in the form in the simple manner described and properly braced, the concrete is then poured into the form. The configuration of each arm not only provides ample surface for adhesion of the concrete to the arm, but, because of the cusps of 35 concrete which form between the tangent circular portions of the cross-section, the arm is mechanically engaged in the concrete. Additional mechanical engagement between the arm 40 and the concrete is also provided by the curved ends of the arm.

From the foregoing it is apparent that a step made according to this invention may be quickly and readily inserted into a form by 45 simply boring into the form two holes for each arm of the step, thus eliminating the keyholing or broaching operations necessary heretofore. Furthermore, step arms having a cross-section according to this invention are stronger than 50 step arms having the rectangular or round cross-sections employed heretofore.

Since the preferred embodiment of this invention may be modified by those skilled in the art, without departing from the essence of it, 55 this invention is not limited to the preferred

embodiment disclosed, either in whole or in part, but is limited only by the following claims.

What is claimed is:

1. As an article of manufacture, a step adapted to be supported in a cast concrete structure comprising a tread and an arm supporting said tread, said arm being adapted to be inserted through a form for concrete and to protrude from a concrete structure and having a cross-section, the contour of which comprises 10 connected arcs of a plurality of circles. 5

2. As an article of manufacture, a step adapted to be supported in a cast concrete structure comprising a tread portion and an arm supporting said tread portion, said arm 15 being adapted to be inserted through a form for concrete and to protrude from a concrete structure and having a cross-section comprised of a plurality of substantially tangent circular portions and fillets included between said circular portions. 20

3. In an article of manufacture of the class described, an arm adapted to be inserted through a form for concrete and to be anchored in a concrete structure, said arm having a 25 cross-section, the contour of which comprises connected arcs of a plurality of circles, whereby cusps of concrete will be mechanically engaged between the arcuate portions of said arm. 30

4. In an article of manufacture of the class described, a substantially U-shaped step adapted to be supported in masonry, said step comprising a tread and a parallel pair of arms supporting said tread, each of said arms having a cross-section, the contour of which comprises 35 a plurality of connected arcs of a circle. 35

5. In an article of manufacture of the class described, a substantially U-shaped step adapted to be supported in masonry, said step comprising a tread and a parallel pair of arms 40 supporting said tread, each of said arms having a section consisting of two substantially tangent circular portions and fillets included between said circular portion, the ends of the arms being similarly curved in substantially parallel 45 planes. 50

6. In an article of manufacture of the class described, a substantially U-shaped step adapted to be supported in masonry, said step comprising a tread and a parallel pair of arms 50 supporting said tread, each of said arms having a cross-section, the contour of which comprises connected arcs of a plurality of adjacent circles. 55
